UNITED STATES PATENT OFFICE.

HARRY F. SMITH, OF DAYTON, OHIO, ASSIGNOR TO THE GAS RESEARCH COMPANY, OF DAYTON, OHIO, A CORPORATION OF OHIO.

CALORIMETER.

Application filed August 11, 1922. Serial No. 581,175.

This invention relates to calorimeters, and more particularly to calorimeters adapted for indicating or recording the heat value of combustible gases.

5 One of the principal objects of the invention is to provide an improved form of calorimeter, of this character, which is simple and cheap in construction, easy of maintenance, accurate in its operation, and constructed to indicate or record directly the heat value of gases, automatically corrected to standard conditions.

10 Other objects and advantages will be apparent from the description thereof set out 15 below when taken in connection with the accompanying drawing.

In the drawing in which like characters of reference designate like parts throughout the several views thereof;

20 Fig. 1 is a view in elevation, with certain parts shown in section to more clearly disclose the construction of those parts, of a form of apparatus adapted for continuously recording the heat value of a gaseous fuel;

25 Fig. 2 is a side view of the calorimeter proper with certain parts thereof shown in section to more clearly show the construction and operation thereof;

30 Fig. 3 is a sectional view of the calorimeter proper along the line 3—3 of Fig. 2 looking in the direction of the arrows;

Fig. 4 is a sectional view through the calorimeter proper along the line 4—4 of Fig. 2, looking in the direction of the arrows;

35 Fig. 5 is a detail sectional view, along the line 5—5 of Fig. 3;

Fig. 6 is a sectional view of part of the mechanism of the calorimeter proper, along the line 6—6 of Fig. 4;

40 Fig. 7 is a sectional and plan view of a modified form of calorimeter proper; and

Fig. 8 is a sectional and elevation view of this same modified form.

In the patent to Harry F. Smith No. 45 1,134,768 dated April 6, 1915 is shown a method of determining the heat value of a combustible gas, and apparatus for carrying that method into effect. The apparatus forming the subject matter of this invention is also intended to carry into effect the method set out in this referred to patent.

That method consists, broadly, in introduc-

ing the combustible gas and atmospheric air, or its equivalent, in predetermined proportions, into the combustion chamber of the 55 calorimeter proper, burning those gases in such wise that the resulting heat of combustion affects a temperature responsive device to indicate directly the heat value of the combustible gas, the instrument being so calibrated that the number of heat units contained in a given quantity of the combustible gas is directly indicated or recorded.

The heat indicating apparatus constructed in accordance with this invention, as shown 65 most clearly in Fig. 1, consists of a calorimeter proper designated by the numeral 20, and what, for purposes of convenience in description, is designated as a "sampling pump," which sampling pump actually 70 comprises a gas pump designated generally by the numeral 21 and an air pump designated generally by the numeral 22, these two pumps being so arranged and operated that the gas and air are delivered 75 by them in definite predetermined proportioned quantities, the two pumps preferably having a common drive shaft.

Any standard type of pumping apparatus can be used for delivering the air and gas 80 to the combustion chamber, and this is especially true of the pump 22, for delivering the air. With a low heat value gas, such as producer gas, having a heat value which ranges, ordinarily, up to 200 B. t. u. per cubic foot, 85 the air and gas are preferably supplied to the combustion chamber in the proportions of substantially thirty to one. Because of the proportionately large quantity of air to gas, in such cases, slight variations in the actual 90 quantity of air supplied are not of material importance since a considerable variation would be needed in order to produce an appreciable error in the indications or recording of the calorimeter proper. Therefore 95 this pump 22 may be either a good piston pump or a good gear pump. As disclosed in the drawing, this pump is preferably a conventional rotary or gear pump, of the so called "Roots blower" type, the details of 100 construction of the pump therefore not being shown. The pump is driven from a shaft 30, which in turn is driven by the motor 31 through a suitable gear reduction

illustrated diagrammatically at 32. But because of the relatively small quantity of gas, it is obvious that even slight variations in the quantity of gas introduced will result in 5 comparatively substantial variations in the total quantity of heat generated within the combustion chamber, and will therefore result in substantial errors in the indicating or recording of the calorimeter proper. While, 10 therefore, theoretically, any really accurate pump will function satisfactorily, as a matter of fact in practice none of the pumps generally available on the market that has been tried has been sufficiently accurate for this 15 purpose. And therefore, the pump designated generally by the numeral 21 was designed for the particular purpose of securing a sufficiently accurate feeding of the gas to the calorimeter proper. This pump, 20 which is fully disclosed and described in the copending application of Harry F. Smith Serial No. 436,236 filed January 10, 1921, comprises a pump barrel or cylinder 35 which has a piston or plunger receiving bore 25 36. At one end the barrel is enlarged to provide a chamber 37 which constitutes a continuation or enlargement of the passage or bore 36. Adjacent its other end the barrel 35 has an enlargement 38 formed integrally 30 therewith which enlargement serves as a top or cover for the chamber 39 surrounding the lower or delivery end 40 of the pump barrel. Within the cylinder barrel adjacent the delivery end thereof is a circular groove 41, 35 which completely surrounds, and is connected to the bore 36 of the barrel. Opening into the groove 41 is an inlet passage 42, formed within the cover 38, to which is connected the gas delivery pipe or main 43, through 40 which gas from any suitable source of supply is led to the inlet passage 42 of the pump. Also opening through the cover 38 is an outlet passage 44 to which is connected the pipe 45, which opens into the combustion chamber of the calorimeter proper. Closing the delivery end of the pump barrel is a disc valve 46, which is normally urged against the seat 47, formed upon the lower or delivery end of the cylinder barrel, by means of 45 a spring 48, one end of which bears against the valve disc and the other against a spider, illustrated somewhat diagrammatically, at 49. This spider is preferably carried upon bolts, 50, but any other suitable means of holding it in place may be used. Adjusting nuts are mounted upon the lower ends of the bolts by means of which the tension of the spring 48 may be varied as desired, to make 55 sufficiently positive the seating of the valve disc against its seat.

The chamber 39 is adapted to contain a sealing fluid 51, which is carried at such depth that it at all times covers the lower or delivery end of the barrel and the valve disc 60 46 closing the barrel. This construction is

such that the gas may readily pass from the cylinder barrel through the delivery end thereof, through the chamber 39, and then out through the delivery pipe 45 the valve 46 being held away from its seat by the pressure of the outgoing gas. But passage of the gas in the opposite direction, that is from the chamber 39 back into the pump barrel, is prevented, not only by the valve itself but also by the sealing liquid 51. It is not essential that this sealing liquid be used, for in actual practice the pump is usually sufficiently accurate when this liquid is not present.

80 Mounted within the bore 36 of the pump barrel is a piston or plunger 55, provided with a plurality of grooves 56. The upper end of the piston is operatively connected to one end of the connecting rod 57, the other end of which is connected to the crank pin 58 carried by the crank disc 59, which is in turn mounted upon the shaft 30. The opening 60, within the side of the enlargement 37, through which the shaft 30 extends, is provided with a cover plate 61, having a passage therein adapted to receive the shaft 30 and serve as a bearing therefor. This cover plate is held in place by means of suitable bolts.

85 During operation of the pump the chamber 37 contains a quantity of sealing liquid 65, sufficient to at all times cover the upper end of the piston. This sealing fluid may be introduced through the opening 66 by removing the cover plate 67, which is normally held in place by suitable bolts. A gauge 70, for indicating the height of the sealing liquid within the enlargement 37, is also provided.

90 The sealing liquid within the enlargement 39 and also within the enlargement 37 should vary in character according to the material being pumped. Where gas such as natural gas, city gas, producer gas, or the like is being handled the sealing liquid may be a suitable form of oil. But in any event the sealing liquid should be such that there will be no absorption or solution of the gas as it passes therethrough.

95 During operation the piston 55 on the upstroke uncovers the passage 41 and permits the inflow of gas into the lower end of the pump barrel, below the piston. At all times during upstroke of the piston the valve 46 is closed, and is covered by the fluid within the enlargement 39, so that backflow into the pump barrel through the delivery end, from the chamber 39 cannot occur. Upon down stroke of the piston the initial part of the stroke causes the piston to cover over the inlet passage, after which compression of the gas within the lower end of the pump barrel occurs. As the piston continues its downward stroke the valve 46 is forced away from its seat and the gas is forced out through the sealing liquid,

through the outlet passage 44 into the pipe 45 to be delivered into the combustion chamber of the calorimeter. The stroke of the piston is so regulated that at the completion of the down stroke the end thereof preferably extends a short distance beyond the valve seat 47, so that there is complete expulsion, on every down stroke, of all the gas within the pump barrel.

- 10 This pump is not only so constructed that mechanical friction is minimized, packed joints being dispensed with, but leakage is also practically eliminated, and complete expulsion of the charge within the cylinder 15 is effected on each stroke, so that each stroke of the pump will deliver a definite quantity of gas.

Inasmuch as the pump 21 and the pump 22 are both driven from the same shaft 30, 20 they are constrained to operate at proportionate rates, and therefore to deliver proportionate quantities of air and gas.

Furthermore, air and gas are delivered under substantially the same conditions of 25 temperature and pressure, since the air handled by the pump 22 is under the pressure and temperature which exists within the room housing the calorimeter, and the gas is also delivered to the pump under the 30 same temperature and is pumped against the same atmospheric pressures.

The calorimeter proper consists of a cylindrical shell 80, in the lower end of which is located a ported plate 81, which is secured 35 to the shell in any desired manner, the method of attachment being a matter of indifference so long as a tight joint is secured. Preferably this plate is pressed into place with a gas tight fit. Attached to the 40 plate 81, by means of suitable bolts is a closure member 82 having a passage 83 therein, which receives the end of the delivery pipe 45 of the gas pump 21, the combustible gas being introduced through this 45 passage into the combustion chamber 84, within the cylindrical member 80.

The upper end of the cylindrical member 80 has therearound a cylindrical sleeve 90, the open upper end of which is closed 50 by the plate 91, which is connected to the sleeve 90 in any suitable manner, the connection shown being by means of stud bolts 92. Threadedly received within a suitable 55 opening in the sleeve 90 is a pipe 93, the other end of which is connected to the delivery port of the air pump 22, the end of this pipe connected to the sleeve 90 opening into the space within the sleeve so that during 60 operation of the device air in predetermined quantity is introduced therethrough into the cylindrical member 80. Positioned within the cylindrical member 80, and attached to the depending flange 95, surrounding the opening 96, in the plate 65 member 91, is a cylindrical tube 97, which is

arranged substantially coaxial with the cylindrical member 80 and extends downwardly thereinto with its lower end terminating a short distance from the plate 81. Surrounding the cylindrical tube 97, and arranged in spaced relation between this tube and the cylindrical member 80 are a plurality of corresponding tubular members 98, each of which is carried by or contacts with the plate member 91 and each of 70 which also terminates a short distance above the upper surface of the plate 81. Mounted upon the member 81 and extending upwardly therefrom are two cylindrical tubes 100, which are so arranged that one 80 of these tubes extends upwardly into the space between the tubular member 97, and the adjacent tubular member 98, the other extending upwardly between the two tubular sleeves 98. By means of this construction 85 the air passing in through the pipe 93 into the space within the ring 90 is caused to traverse a labyrinth path on its way to the combustion chamber 84, which is contained within the tubular member 97. As 90 the air thus passes first downwardly around the tubular members 98 and thence upwardly around the associated members 100, to finally pass into the combustion chamber 84 at the lower end thereof adjacent the point 95 of entrance of the gas into said combustion chamber, it absorbs heat which tends to escape into the atmosphere by transfer from one of the tubular sleeves to another, so that a true indication is obtained of the actual heat liberated within the calorimeter 100 during the burning of the gas. The various tubular members 98 and 100, and also the tube 97 are provided with holes at the tops and bottoms thereof so arranged that with 105 the device in assembled position the respective holes will be in alignment. Tapered pins 101 are positioned within these holes serving to properly space the tubular members from each other and to maintain them 110 in position.

Extending upwardly from the plate 81 into the combustion chamber 84 is a pipe 105, into the lower end of which the passage 83 opens. The combustible gas introduced 115 through the pipe 45 passes upwardly through this member 105 into the combustion chamber, the air entering the combustion chamber around the lower end of the member 97 passing upwardly around the outside of the member 105, the gas introduced through the member 105 burning in this air, within the combustion chamber 84, the hot products of combustion passing upwardly 120 through a depending cylindrical tube 106, which is positioned within the opening 96, in the top plate 91. Inasmuch as the incoming air prevents any heat loss by radiation from the member 84, the hot products 125 of combustion and the heated excess air, 130

which pass upwardly through the member 106, have a temperature which is directly dependent upon the actual heat generated by the burning of the gas within the combustion chamber.

Located within this member 106, is a heat responsive element 107, which consists of a strip or ribbon of some heat resisting material, such as a nickel-alloy steel, or the like. 10 This ribbon is folded upon itself about a transverse pin or shaft 108, which extends entirely across the member 80, and has its ends positioned within suitable openings therein suitable nuts 109, being provided to 15 hold this pin securely in place. Each of the tubular members 98, 100 and each of the members 97 and 103 is provided with suitable openings to receive this pin 108, each of these openings being of greater diameter 20 than the pin itself, so that any expansion or contraction of these various tubular members during operation of the device will have no effect at all upon the relative positioning of the pin 108, and therefore will 25 not in any way affect the indicating or recording mechanism. The free ends of the heat responsive strip are riveted to a steel block 112, to which is also riveted a single steel strip 113, the upper end of which is 30 firmly riveted to a cross bar 114, which extends at each end through an opening in the chimney or vent pipe 115, which surrounds the opening 106, and through which the heated gases from the combustion chamber 35 84 pass on the way to the atmosphere. Preferably the block 112 consists of two blocks of equal thickness which are riveted together with the strip 113 between them and the bar 114 also consists of two bars of 40 equal thickness which are riveted together with the upper end of the strip 113 between them. The outer ends of the bar 114, which extends through the openings 116, and beyond the vent pipe 115, are pivoted within 45 the member 120, which preferably consists of a forked, or substantially U-shaped member, one end of which is connected by means of two flexible strips or straps 121 to the member 122, which is pivotally supported at one end upon the pivot points 123, which are in turn rigidly secured in the standards 124. The other end of the member 120 is provided with an adjusting screw 125, which contacts with the upstanding standard 126, carried upon the base member 127, which member also carries the upstanding standard 124. As a function resulting from this construction the member 50 122 may be swung, as desired, about the pivot 123, and by suitably manipulating the adjusting screw 125 this member 122 may be caused to assume any desired position, and thus the end of the member 126, which 55 is suspended from the member 122 by means of the straps 121 may also be caused to as-

sume any desired position. The straps 121 may be secured to the members 120 and 122 in any desired manner, but they are preferably secured by means of small bolts 128, which extend through cooperating holes in 70 the flexible strips and extend into correspondingly threaded sockets in the ends of these members. Preferably clamping members 129 are provided so that any flexing of these flexible strips will be directly across 75 the strip, to thus give a definite effective length to each strip after it is secured in position. While this member 120 was described above as substantially U-shaped it is in reality more in the nature of a rectangle, the sides thereof being substantially parallel and spaced a sufficient distance apart to freely receive the vent pipe 115 but its precise shape is not important. The other end of this member 120 opposite to 80 the end which has the strips 121 attached thereto is provided with a cross bar 130, to which is attached a trough like member 131, the cross bar 130 fitting within this trough like member to give a closed chamber, within 85 which is mounted a small worm gear 132, having a passage 133 therein adapted to receive a manipulating key for rotating this gear, this worm gear meshing with a corresponding spiral toothed gear 134 rigidly 90 mounted upon the stub shaft 135, which shaft is journaled within suitable openings in the side walls of the trough like member 131, and is held against lengthwise movement relative to the trough 131 by means of the gear 134, this gear being so proportioned as to fit snugly within the trough 131 and rigidly secured to the shaft 135. The free end of the member 135 is threadedly mounted 95 within a sliding block 138, which is constructed to slide along the lower face of the member 120, the sides of this member being cut away as shown at 139, to provide a track. Suitable manipulation of the worm gear 133 will cause rotation of the shaft 135, and since that shaft is held against axial movement, the sliding block 138 will be moved lengthwise of that shaft to vary 100 its position. Suitably connected to the sliding block 138 is a flexible strip 142, the other end of this strip being connected to a corresponding sliding block 143, which has threadedly mounted therein a similar threaded shaft 144. One end of this shaft 105 extends through a trough like member 145, which extends upwardly from one end of the member 146, that member being substantially similar in construction to the member 120, with the exception that the track 147, thereof, on which the sliding block 143 is 110 mounted and along which it slides, is upon the upper face of the member 146, whereas the corresponding track 139 is upon the lower face of the yoke member 120. The trough 145 is also provided with a worm 115

105

110

115

120

125

130

gear 148, and a corresponding helical gear 149, which are identical in construction with the similar parts in the trough member 131 and are also arranged so that a manipulating key may be inserted within the passage in the worm gear 148 to cause suitable adjustment of the sliding block 143. As shown, particularly in Fig. 5, the ends of the members 120 and 146 are positioned one over the other, and the construction of the gear housings or troughs 131 and 145 is such that the two worm gears 132 and 148 are coaxially arranged so that they may both be manipulated at the same time by passing a suitable key 150 through the aligned openings in these two members to manipulate them both at the same time and thus secure similar manipulation of the sliding blocks. This type of adjustment apparatus is not essential, but if desired the two blocks may be adjusted independently, or other means provided for varying the adjustment.

One end of the member 146 has attached thereto a flexible strip 155, the other end of which strip is wrapped partway around the cylindrical bar or rotatable shaft 156, which is supported, at its opposite ends, upon the pivot points 157, free rotation of this bar thus being permitted. The strip 155 which is wrapped partly around the shaft 156 has one end thereof secured to that shaft in any suitable manner, as by means of the screw 158. This end of the member 146, is thus firmly supported, but its position will be entirely dependent upon the relative position of the shaft 156, for as this shaft is rotated in one direction or the other, the end of the member 146 which is connected thereto will be raised or lowered correspondingly. And of course raising or lowering the end of the member 146 will cause corresponding rotation of the shaft 156. The other end of the member 146 has two flexible straps 160 connected thereto, in substantially the same manner as heretofore described in connection with the strips 121, the other ends of these two straps being correspondingly connected to the yoke member 162. The arms 163 of this yoke member are supported upon pivot points 164. These pivots, as are the other pivots 123 and 157, are preferably formed of hardened steel, and since there is practically no movement of the various pivoted members about their supports, except during adjustment of the device, the wear is entirely negligible. And steel pivots of this character will be found very satisfactory under actual operating conditions. The base member 127 is also provided with two standards 165, to the upper end of each of which is attached a spring 166. The other end of each of the springs 166 has attached thereto a flexible metallic strip 167, the lower end of which is

wound partly around the cylindrical shaft 156 and is firmly attached thereto as by means of suitable screw or bolt as shown.

These springs 166 are so constructed and mounted that they are normally under tension tending to rotate the shaft 156 in such wise as to lift up on the end of the member 146 connected thereto. This corresponds with the lengthening of the thermostatic strip 107 under the influence of the combustion within the chamber 84.

The shaft 156, as shown particularly in Fig. 2 has rigidly secured thereto an indicating needle or pen 170, which cooperates with a dial 171, upon which may be positioned suitable indicating cards, such a card being shown diagrammatically in Fig. 1 by the numeral 172. This dial 171 is mounted upon a shaft 173, which is driven by a suitable clock mechanism designated generally by the numeral 174 so that rotation at a predetermined rate is secured. This particular part of the apparatus is used, of course, only where the calorimeter is constructed for giving a continuous record, the pen tracing a line over the card 172 as the dial 171 rotates. If it is desired to have an instrument for giving only indications of the character of the gas being burned therein, without the making of a continuous record, then this particular member of the mechanism could be dispensed with and an indicating gauge provided with an ordinary pointer substituted in place of the pen 170, and clock and dial mechanism cooperating therewith. This particular part of the mechanism is conventional in construction, and the clock mechanism and the like is not shown in any greater detail on that account.

Of course any desired means of igniting the gas within the combustion chamber 84 may be used, but preferably the means disclosed in the drawing is used which consists of a spark plug, provided with suitable ignition coil and the like. The member 105 serves as one terminal of the spark plug, this member being grounded to the closure 81, which in turn carries a connecting post 200, to which is connected one end of the conductor 201 the other end being connected to one terminal of the high tension coil of the spark coil 202. The other terminal of the high tension coil of the spark coil 202 has a conductor 203 connected thereto, the other end of which is connected to the binding post 204, carried upon the wire 205, which is mounted within a suitable plug 206, of insulating material, this plug being in turn held within a suitable opening in the closure plate 81, so that the inner end of the wire 205 terminates adjacent the edge of the member 105. Upon actuation of the spark coil 202 sparks will be caused to pass between the cooperating ends of the wire 205 and the member 105 to ignite the com-

bustible mixture of air and gas immediately adjacent thereto. The spark coil 202 has the low tension coil thereof connected, by suitable conductors 210 and 211 to any suitable source of electrical potential such for instance as a battery which is illustrated conventionally at 212. A suitable switch 214 is provided for closing the circuit through the battery and low tension coil of the spark coil to cause energizing thereof. If desired the motor 31 may be operated from the same source of electrical potential as the spark coil 202. As shown this motor is connected by suitable conductors 215 and 216 to the terminals of the battery 212, a switch 217 being inserted within the motor circuit so that upon closing the switch the motor will be energized to operate the two pumps 21 and 22 and thus deliver a predetermined mixture of air and gas to the combustion chamber.

The operation of the device is as follows. Assuming that it is starting anew, the strip 107 will be contracted, and the force exerted by this strip during the contacting will have caused such actuation of the lever mechanism described above as to rotate the shaft 156 to bring the pen 170 to substantially zero position. The switch 217 is now closed to cause the motor 31 to actuate the pumps 21 and 22 to force the predetermined quantities of gas and air into the combustion chamber 84. The switch 214 is then closed to cause a spark to pass between the members 205 and 105 to ignite the combustible mixture within the combustion chamber. The hot products of combustion pass upwardly through the member 106 and out through the vent pipe 115 imparting heat to the strip 107 as they travel over it. This strip will therefore lengthen due to expansion and inasmuch as the springs 156 are so arranged that they are normally under tension tending to rotate the shaft 156 this expansion of the strip 107 will immediately result in rotation of that shaft to move the needle across the dial, the movement of the needle continuing until substantially equilibrium condition is secured within the combustion chamber, that is until the members have been heated up to a temperature which corresponds with the heat being generated by the burning gas. Thereafter any fluctuations in heat value will be directly indicated. The construction of the apparatus, to secure this condition, as described above, is such that with the springs 166 tending to rotate the bar 156 there is a corresponding tendency to lift the end of the member 146 which is connected to this bar by means of the straps 155. The other end of this bar is suspended from a supporting member 162 by means of the straps 160 and this end therefore serves as a fulcrum while the sliding block 143, which has the strap 142

connected thereto constitutes the point of application of the weight. This member 146, therefore, tends to rotate about the point of attachment of the strap 160 as a fulcrum and to raise the strap 142. But the strap 142 is connected at its lower end to the sliding block 138, which is in turn positioned below the member 120 so that any upward movement of that sliding block must cause corresponding upward movement of the end of the member 120 with which it cooperates. But since the member 120 has the strip 107 connected intermediate its ends, its other end being suspended from the flexible strip 121 any tendency to lift the end of the member 120, to which the straps 142 are connected will result in swinging that member about the bars 114 as centers, the point of attachment of the strip 121 to this member at that time constituting the fulcrum about which this member swings. It is thus evident that the rotation of the bar 156 will be directly dependent upon the relative expansion or contraction of the strip 107 and since the combustion chamber 84 is surrounded by the labyrinth passages through which the air passes thereinto, so that there is no escape of the heat generated by the combustion within this chamber outwardly through the walls of the chamber, therefore the expansion and contraction of the member 107 as a result of fluctuations in its temperature is directly proportional to fluctuations in the amount of heat generated during the burning of the gas within the combustion chamber. Therefore an accurate and correct recording of the fluctuations in the heat value of the gas is made.

And since the gas and air are fed into the combustion chamber under atmospheric temperature and pressure or under the same temperature and pressure any fluctuation in temperature or pressure will affect both alike. Therefore it is not necessary to make any corrections for temperatures or pressures since the instrument will automatically make these corrections and indicate the correct heat value regardless of fluctuations in temperatures or pressures of the gas and air.

In Figs. 7 and 8 is shown a slightly modified form of calorimeter proper in which a simple leverage is substituted for the compound leverage shown in the modification of the invention disclosed in Figs. 1 through 6. In this modification the heat responsive element is identical in construction with the corresponding element 107 described above and is connected to a single steel strip 113', the upper end of which is rigidly secured to a cross bar 300, the connection being preferably by such riveting as is described in connection with the strip 113 and cross bar 114. This cross bar 300 has its

opposite ends positioned within slots in blocks 301, each of which blocks is slidably mounted within a groove or channel 302 formed in the upper face of the lever designated generally by the numeral 303. This lever consists of a body portion which is cut away as designated by the numeral 304 to receive the upper end of the vent pipe 115', and which is supported by means of 10 suitable flexible straps 310 each of which is connected at one end to the lever, and at the other end to the plate 311, this plate being in turn pivotally mounted upon pivots 312, which are similar in construction to the 15 pivot member described above. These pivots 312 are mounted within standards or supports 313, one of these standards being provided with a shoulder 314 with which cooperates the adjusting screw 315. This adjusting screw is threadedly mounted within 20 a suitably threaded opening, or passage within the plate 311, and by properly manipulating it any desired setting of the lever may be secured.

The lever 303 is also provided with an extension 320, the free end of which has suitably secured thereto a flexible strap or 25 steel strip 321, the lower end of which is coiled part way around and attached to the cylindrical bar or shaft 322. This bar is 30 rotatably mounted upon suitable pivots 323, and has attached thereto the indicating needle or pen 324, the construction being such that as the heat responsive strip varies 35 in length with concomitant swinging of the lever about its points of support, which points of support are the points of attachment of the flexible strips 310, this shaft will be caused to rotate to indicate or record 40 the heat value of the gas.

The body member of the lever is preferably provided with an end member or cross bar 330, which has mounted therein a stub shaft 331, provided with a suitable manipulating enlargement or finger piece 332. Mounted upon this stub shaft 331 is a gear wheel or pinion 335 which meshes with the gear 336, which is in turn mounted upon a rotatable shaft 337 the opposite end of 45 which is threadedly mounted within a correspondingly threaded opening or passage in one of the members 301. The pinion 335 also meshes with a gear wheel 338, which is mounted upon a rotatable shaft 339, the other 50 end of which is threadedly mounted within a suitable threaded passage in the other member 301. The pinion 335 and the two gears 336 and 338 are so constructed that upon manipulation of the gear 335 the two members 301 will be moved in the same direction, the same distance, to shift the relative point 55 of attachment of the heat responsive strip to the lever. By means of this adjustment device the effective length of the lever may

be varied to effect calibration of the apparatus.

The cylindrical bar 322 also has attached thereto a flexible strip 340, the lower end of which carries a weight 341, which serves to counterpoise the lever mechanism. This weight is adapted to function as do the springs 166 described above.

Where the compound leverage illustrated in Figs. 1 through 6, and described above, is used, the device may be made somewhat more compact than where a simple lever such as illustrated in Figs. 7 and 8 is used. Where the overall dimensions of the compound leverage mechanism described above is, say, six inches, the overall dimensions of the corresponding simple lever mechanism would be probably twelve to fourteen inches. In order to make a simple lever instrument which is in appearance well balanced, and better looking, therefore, a second member 80 85 350 is provided, which is similar in outward appearance to the shell 80', the indicating or recording dial being symmetrically positioned with respect to these two members.

The member 350 may be merely a dummy 90 used for appearance, but if desired, it may be provided with a series of baffles and the air, which is introduced to the shell 80', first passed through this member 350 to remove therefrom dust and other impurities. 95 In this case the construction should be such that passing air will not affect the influence of the weight 341. This may be easily accomplished by positioning a transverse partition across the member 350, below the 100 weight.

In operation the device illustrated in Figs. 7 and 8 is substantially identical with the device illustrated in Figs. 1 through 6, and described above.

It will be noted that the various elements of the mechanism connecting the indicating needle to the heat responsive element are connected to each other by flexible straps, the ends of which are rigidly secured to the respective cooperating members. And pivots of conventional character are used only for the adjusting member and the rotatable shaft carrying the indicating needle, as a consequence the wear which is inevitable 110 where conventional pivots, of the kind in which a pointed member seats in a cooperating socket, are used is practically eliminated. In actual practice calorimeters of the general character described but with conventional pivots have to be checked up and recalibrated at frequent intervals to insure accuracy of operation; while with apparatus of the character illustrated herein, accurate operation over long periods, without 115 any necessity for recalibration is secured.

While the forms of apparatus herein described constitute preferred embodiments of

the invention, it is to be understood that the invention is not limited to these precise forms of apparatus, and that changes may be made in either without departing from 5 the scope of the invention which is defined in the appended claims.

What is claimed is:

1. In a calorimeter of the character described, a combustion chamber, a heat responsive strip within said chamber; indicating mechanism, comprising an indicating needle; lever mechanism, means for connecting said lever mechanism to said heat responsive strip, and means for connecting 10 said mechanism to said indicating needle, each of said connecting means comprising a flexible strap.

2. In a calorimeter of the character described, a combustion chamber, a heat responsive strip within said chamber and unconnected therewith; indicating mechanism, comprising an indicating needle; lever mechanism, comprising a plurality of lever elements, means for operatively connecting the 20 said lever elements together, said means comprising flexible straps; means for connecting said lever mechanism to the said heat responsive strip, and means for connecting said lever mechanism to said indicating needle.

3. In a calorimeter of the character described, a combustion chamber, a heat responsive element within said chamber and unconnected therewith; indicating mechanism, comprising an indicating needle; lever mechanism, comprising a plurality of lever elements, means for operatively connecting the said lever elements together, said means comprising flexible straps; means for connecting 30 said lever mechanism to the said heat responsive element, and means for connecting said lever mechanism to said indicating needle, each said connecting means comprising a flexible strap.

4. In a calorimeter of the character described, a combustion chamber, a heat responsive element within said combustion chamber; indicating mechanism, comprising an indicating needle; lever mechanism, a flexible strap connecting one end thereof to the indicating needle, a second flexible strap connecting the other end of said lever mechanism to a support, and a flexible strap connecting 40 said lever mechanism intermediate its ends to the heat responsive element.

5. In a calorimeter of the character described, a combustion chamber, a heat responsive element therein; indicating mechanism, comprising an indicating needle; and lever mechanism operatively connecting the 50 said heat responsive element and indicating needle, said mechanism comprising an adjustable supporting member, a flexible strap connecting one end of the lever mechanism to said supporting member, a flexible strap connecting 60 one end of the lever mechanism intermediate its ends to the heat responsive strip.

connecting the other end of said lever mechanism to the indicating needle, and a flexible strap connecting said lever mechanism intermediate its ends to the heat responsive element.

6. In a calorimeter of the character described, a combustion chamber, a heat responsive element therein; indicating mechanism, comprising an indicating needle; and lever mechanism operatively connecting the 70 said heat responsive element and indicating needle, said mechanism comprising a pivoted supporting member, having an adjusting screw therein, a flexible strap connecting one end of the lever mechanism to said supporting member, a flexible strap connecting the other end of said lever mechanism to the indicating needle, and a flexible strap connecting said lever mechanism intermediate its ends to the heat responsive strip.

7. In a calorimeter of the character described, a combustion chamber, a heat responsive element therein; indicating mechanism, comprising an indicating needle; lever mechanism, means for operatively connecting said lever mechanism to the said heat responsive element, means for operatively connecting said lever mechanism, to said indicating needle, and means for varying the effective length of said lever mechanism.

8. In a calorimeter of the character described, a combustion chamber, a heat responsive element therein; indicating mechanism, comprising an indicating needle; and lever mechanism operatively connecting the 90 said heat responsive element and indicating needle, said mechanism comprising a pivoted supporting member, having an adjusting screw therein, a flexible strap connecting one end of the lever mechanism to said supporting member, a flexible strap connecting the other end of said lever mechanism to the indicating needle, a flexible strap connecting said lever mechanism intermediate its ends to the heat responsive strip, and means for varying the effective length of said lever mechanism.

9. In a calorimeter of the character described, a combustion chamber, a heat responsive element therein; indicating mechanism, comprising an indicating needle; and a lever mechanism operatively connecting the heat responsive strip to the indicating needle, said lever mechanism comprising a compound lever having two lever elements, means for supporting one end of one of said elements, means for connecting the other end of said element to the indicating means, means connecting the said element intermediate its ends to one end of a second lever element, means connected to the other end of said second named element for supporting it, and means for connecting the said second named element, intermediate its ends, to the heat responsive strip.

10. In a calorimeter of the character described, a combustion chamber, a heat responsive element therein; indicating mechanism, comprising an indicating needle; and
 5 a lever mechanism operatively connecting the heat responsive strip to the indicating needle, said lever mechanism comprising a compound lever having two lever elements, means for supporting one end of one of said elements, means for connecting the other end of said one element to the indicating means, means connecting the said one element intermediate its ends to one end of a second lever element, means connected to
 10 the other end of said second named lever element for supporting it, and means for connecting the said second named lever element, intermediate its ends, to the heat responsive strip, each of said connecting means
 15 comprising a flexible strap.

11. In a calorimeter of the character described, a combustion chamber, a heat responsive element therein; indicating mechanism, comprising an indicating needle; a
 20 compound lever mechanism operatively connecting the heat responsive element to the indicating needle, said lever mechanism comprising two lever elements, a flexible strap for connecting one of said lever elements to the said indicating needle, an adjustable supporting member, means connecting one end of the said one lever element to the said adjustable supporting member, a flexible strap connecting the said one lever element intermediate its length to one end of the second of said elements, a second adjustable supporting member, means connecting the other end of said second lever element to the said second named supporting member, and means connecting the said second lever element intermediate its length to the heat responsive element.

12. In a calorimeter of the character described, a combustion chamber, a heat responsive element therein; indicating mechanism, comprising an indicating needle; a compound lever mechanism operatively connecting the heat responsive element to the indicating needle, said lever mechanism comprising two lever elements, a flexible strap for connecting one of said lever elements to the said indicating needle, an adjustable supporting member, a flexible strap for connecting one end of said one lever element to the said adjustable supporting member, a flexible strap connecting the said one lever element intermediate its length to the second of said lever elements, a second adjustable supporting member, a flexible strap connecting the said second lever element to the said second named supporting member, and means connecting the said second lever element intermediate its length to the heat responsive element.

13. A calorimeter of the character de-

scribed, a combustion chamber, a heat responsive element therein; indicating mechanism, comprising an indicating needle; a compound lever mechanism operatively connecting the heat responsive element to the indicating needle, said lever mechanism comprising two lever elements, a flexible strap for connecting one of said lever elements to the said indicating needle, a pivoted supporting member, means for swinging said supporting member about its pivot, a flexible strap connecting one end of the said one lever element to the said pivoted supporting member, a flexible strap connecting the said one lever element intermediate its length to one end of the second of said lever elements, a second pivoted supporting member, means connecting the other end of said second lever element to the said second named pivoted supporting member, and means connecting the said second lever element intermediate its length to the heat responsive element.

14. In a calorimeter of the character described, a combustion chamber, a heat responsive element therein; indicating mechanism, comprising an indicating needle; lever mechanism operatively connecting the said heat responsive element to said indicating needle, and means for varying the effective length of said lever mechanism.

15. In a calorimeter of the character described, a combustion chamber, a heat responsive element therein; indicating mechanism, comprising an indicating needle; and a lever mechanism operatively connecting the heat responsive element to the indicating needle, said lever mechanism comprising a compound lever having two lever elements, means for supporting one end of one of said lever elements, means for connecting the other end of said lever element to the indicating needle, means connecting the said one lever element intermediate its ends to one end of a second lever element, means connected to the other end of said second named lever element for supporting it, means for connecting the said second named lever element, intermediate its ends, to the heat responsive element, and means for varying the effective length of said lever mechanism, comprising a slid able member, mounted upon one of said lever elements to which is attached one end of the flexible strap connecting the two lever elements together.

16. In a calorimeter of the character described, a combustion chamber, a heat responsive element therein; indicating mechanism, comprising a rotatable shaft and an indicating needle mounted thereon; an operating lever, means connecting the said heat responsive element to the said lever, and means operatively connecting the said lever to the said rotary shaft, the construction being

such that actuation of the lever by the heat responsive element will cause rotation of the needle carrying shaft to indicate directly the heat value of the gas being burned within the combustion chamber of the calorimeter.

17. In a calorimeter of the character described, a combustion chamber, a heat responsive element therein; indicating mechanism comprising a rotary shaft and an indicating needle carried thereby; and means operatively connecting the said heat responsive element to the said rotary shaft, the construction being such that in response to variations in the amount of heat generated within the combustion chamber the heat responsive element will cause rotation of the needle carrying the shaft to move the indicating needle to indicate directly the heat value of the gas being burned within said combustion chamber.

18. In a calorimeter of the character described, a combustion chamber, a heat responsive element therein; indicating mechanism, comprising a rotatable shaft and an indicating needle attached thereto; lever mechanism operatively connected to the said heat responsive element and to the said rotary shaft, each such connection comprising a flexible strap.

19. In a calorimeter of the character described, a combustion chamber, a heat responsive element therein; indicating mechanism, comprising an indicating needle; lever mechanism, means for connecting said lever mechanism to said heat responsive element, and means for connecting said lever mechanism to said indicating needle, each of said connecting means comprising a flexible strap; and means tending to actuate the lever mechanism to hold the indicating needle in zero position.

20. In a calorimeter of the character described, a combustion chamber, a heat responsive element therein; indicating mechanism comprising a rotatable shaft, and an indicating needle attached thereto; and lever mechanism operatively connected to the said heat responsive element to the said rotary shaft, each such connection comprising a flexible strap; and means tending to actuate the lever mechanism to hold the indicating needle in zero position, said means comprising a spring.

21. In a calorimeter of the character described, a combustion chamber, a heat responsive element therein; indicating mechanism, comprising a rotatable shaft, and an indicating needle attached thereto; lever mechanism operatively connected to the said heat responsive element and to the said rotary shaft, each such connection comprising a flexible strap; and means tending to actuate the lever mechanism to hold the indicating needle in zero position, said means comprising a weight, and a flexible strap connecting said weight to the said rotatable shaft.

ing needle in zero position, said means comprising a spring and a flexible strap connecting one end of said spring to the said rotatable shaft.

22. In a calorimeter of the character described, a combustion chamber, a heat responsive element therein; indicating mechanism, comprising an indicating needle; a simple lever, adjustable means for supporting one end of said lever, a flexible strap connecting the other end of said lever to the said indicating needle, and means connecting the said lever, intermediate its ends, to the said heat responsive element.

23. In a calorimeter of the character described, a combustion chamber, a heat responsive element therein; indicating mechanism, comprising a rotatable shaft, an indicating needle carried thereby; a simple lever, adjustable means for supporting one end of said lever, a flexible strap connecting said end of the said lever to said supporting means; a flexible strap connecting the other end of said lever to the rotatable shaft carrying the said indicating needle; and means connecting the said lever intermediate its ends to the heat responsive strip.

24. In a calorimeter of the character described, a combustion chamber, a heat responsive element therein; indicating mechanism, comprising a rotatable shaft, an indicating needle carried thereby; a simple lever, adjustable means for supporting one end of said lever, a flexible strap connecting the other end of said lever to the rotatable shaft carrying the said indicating needle; means connecting the said lever intermediate its ends to the heat responsive strip; and means cooperating with said lever mechanism, tending to rotate the said shaft to return the indicating needle to zero position.

25. In a calorimeter of the character described, a combustion chamber, a heat responsive element therein; indicating mechanism, comprising a rotatable shaft, an indicating needle carried thereby; a simple lever, adjustable means for supporting one end of said lever, a flexible strap connecting said end of the said lever to said supporting means; a flexible strap connecting the other end of said lever to the rotatable shaft carrying the said indicating needle, means connecting the said lever intermediate its ends to the heat responsive strip; and means cooperating with said lever mechanism, tending to rotate the said shaft to return the indicating needle to zero position, said means comprising a weight, and a flexible strap connecting said weight to the said rotatable shaft.

26. In apparatus of the character described a compound lever mechanism, comprising two lever elements; a slideable block mounted upon one of said lever elements, a

second slidable block carried by the second of said lever elements, a flexible strap connected at one end to the first named slidable block and at its other end to the second named slidable block, to operatively connect the two said lever elements together; and means for sliding each of the said blocks along its cooperating lever element to vary the effective point of attachment of said flexible strap to each of said lever elements.

27. In apparatus of the character described a compound lever mechanism, comprising two lever elements; a slidable block mounted upon one of said lever elements, a second slidable block carried by the second of said lever elements, a flexible strap connected at one end to the first named slidable block and at its other end to the second named slidable block, to operatively connect the two said lever elements together; and means cooperating with the two said slidable blocks for moving those blocks together along the said lever elements, to vary the effective point of attachment of

said flexible strap to each of said lever elements. 25

28. In apparatus of the character described, a calorimeter having a combustion chamber constructed for receiving air and a combustible material whose heat value is to be determined; a rotary pump for supplying air to said combustion chamber, a shaft for said pump, an operating motor operatively connected to one end of said shaft, a crank disc, having a crank pin thereon mounted on the other end of said shaft; a reciprocating pump for supplying the combustible material to said combustion chamber, a reciprocable plunger therein, and a connecting rod operatively connecting said plunger to the crank pin carried by the said shaft, the construction being such that both pumps are operated from a common power source to insure delivery of the air and combustible material at proportionate rates. 30 35 40 45

In testimony whereof I hereto affix my signature.

HARRY F. SMITH.
